UNITED STATES PATENT OFFICE

159,948

TOY DERRICK

Murrie C. Betts, Detroit, Mich.

Application September 13, 1946, Serial No. 133,281

Term of patent 3½ years

(Cl. D34—15)

To all whom it may concern:

Be it known that I, Murrie C. Betts, residing at Detroit, in the county of Wayne and State of Michigan, have invented a new, original, and ornamental Design for a Toy Derrick, of which the following is a specification, reference being had to the accompanying drawing, forming part thereof.

The figure is a perspective view of the toy derrick, showing my new design.

I claim:

The ornamental design for a toy derrick, as shown.

MURRIE C. BETTS.
